(57) **CLAIM**

The ornamental design for a light emitting diode, as shown.

DESCRIPTION

FIG. 1 is a front, left perspective view of the light emitting diode showing my new design;

FIG. 2 is a top plan view thereof;

FIG. 3 is a right side view thereof;

FIG. 4 is a left side view thereof;

FIG. 5 is a front view thereof;

FIG. 6 is a rear view thereof; and,

FIG. 7 is a bottom view thereof.
